COVER CONSTRUCTION

Louis A. Shoemaker, Carleton, Mich., and Andrew E. Miller, Terre Haute, Ind.; said Miller assignee or to said Shoemaker

Original application June 8, 1936, Serial No. 84,052. Divided and this application August 5, 1937, Serial No. 157,476

4 Claims. (Cl. 229—44)

This invention relates to baby chick boxes, and more particularly to those that have a cover composed of sections that can be opened and closed separately, so that the interior of the box can be divided into compartments, one or more of which can be opened without opening the others.

This is a division of application Serial No. 84,052, filed June 8, 1936, by L. A. Shoemaker and A. E. Miller for "Chick box".

10 Generally stated, the object of the invention is to provide a novel and improved construction whereby the cover of a chick box of this kind comprises two sections that can be opened and closed separately, but which are integral with each other, through the medium of a double thickness partition in the body of the box, the edges of the cover sections having bendable tabs to engage the side walls of the box, when the cover sections are in closed position, thereby in effect forming 20 notches for a binding wire or the like, to keep the sections closed.

Another object is to provide an improved construction and arrangement whereby the said cover sections have bendable tabs that can be bent down to hold the upper edges of the side walls of the box against outward displacement.

Another object is to provide a novel and improved construction and arrangement whereby the said cover sections are conveniently opened 30 by inserting two fingers under the free or swinging ends of the cover sections, at the middle of each end, with one finger at one side, and the other finger at the other side of an interior partition wall, thereby to disengage said ends from overhanging portions of the box.

It is also an object to provide certain details of construction tending to increase the general efficiency and desirability of a chick box cover construction of this particular character.

40 To the foregoing and other useful ends, the invention consists in matters hereinafter set forth and claimed and shown in the accompanying drawing, in which—

Fig. 1 is a perspective of a chick box having a 45 cover construction embodying the principles of the invention.

Fig. 2 is a longitudinal section on line 2—2 in Fig. 1 of the drawing.

50 Figs. 3, 4 and 5 are fragmentary views of certain portions of the cover construction, Fig. 3 being a vertical section on line 3—3 in Fig. 1 of the drawing, and Fig. 5 being a vertical section on line 5—5 in Fig. 4 of the drawing.

As thus illustrated, the invention comprises 55 the cover sections 25 and 25, integrally connected

together through the medium of the two downwardly converging walls 19 and 19, which latter are integrally united at their lower edges, so that the entire cover, comprising the two sections and the said partition wall, is formed from a single blank, the free or swinging ends of the two cover sections having upturned portions 27 and 27 that engage underneath the horizontal top wall 6 of the body of the box, as shown more clearly in Fig. 2 of the drawing, when the cover sections 10 are in closed position.

The interior of the box has a longitudinal partition wall 28, held in place in any suitable or desired manner, and this wall is provided with shoulders 31 to engage upstanding portions 27 15 and 27, in the manner shown, thus maintaining these portions of the cover in vertical position. Each top wall 6 has its middle portion provided with a notch 8, at the inner edge of the top wall, so that two fingers can be inserted back of either cover portion 27, with one finger at one side, and the other finger at the other side of the partition wall 28, thereby to flex and bend the portions 27 outwardly from under the overhanging inner edges of the walls 6 and 6, which latter serve to hold the free or swinging ends of the two cover sections in closed position.

It will also be seen that the cover sections 25 and 25 have their side edges provided with bendable tabs 26 that can be bent down to in effect provide notches to receive binding wires or other flexible binding members by which to fasten the cover sections in closed position, after the box is filled and ready for shipment or transportation.

In addition, it will be seen that the two cover sections 25 and 25 have bendable tabs 33 that can be bent down to hold the upper edges of the side walls 11 against outward displacement, whereby the cover construction contributes to the strength and stiffness of the general construction 40 of the box.

It will be seen that the tabs 26 and the tabs 33 have outer edges flush with the overhanging side edges of the two cover sections. The tabs 26 form recesses, when pressed down, for the cords or wire, and in this way the tabs 26 prevent the cords or wire from cutting into the upper edges of the side walls. The tabs 33 are spaced apart at each side of the box, when pressed down, and it is their inner edges that effectively engage the 50 side walls.

It will be seen that the projections 34 on the opposite ends of the transverse partition wall 19 and 19, which extend through the side walls of the box, co-operate with the tabs 33 to hold 55

the cover sections in position, when the cover is closed, and that in this way a very effective and tight cover construction is provided. It is also obvious that the tabs 33 serve to hold the cover sections in place, relatively to the openings 8 and 9, so that the latter are centered over the longitudinal partition, thus again insuring accuracy of position of all parts of the cover when the latter is closed.

10 What we claim as our invention is:

1. In a baby chick box, or box for other purposes, means forming bottom and side and end walls for the body of the box, and a folding cover construction comprising two upwardly opening cover sections, the overhanging edges of the cover sections having corner tabs flush with the said edges of the sections that are depressible downwardly away from each other, at each side of the box, to engage with their inner edges the outer surface of the side wall sections, holding the upper middle portion of the latter against outward displacement, with a space between the two depressed tabs at each side of the box.

2. A structure as specified in claim 1, the two cover sections being connected together by an integral double partition wall dividing the box into two compartments, one under each cover section, and the ends of which partition wall are held against the side walls by said tabs.

3. A structure as specified in claim 1, comprising a transverse partition having end portions projecting through the side walls, co-operating with said tabs to hold said cover sections in place, when in closed position.

4. A structure as specified in claim 1, comprising top walls having openings in the inner edges thereof, at the longitudinal center of the box, with a longitudinal partition extending under said openings, said cover sections having upstanding end flaps held in proper position relative to said openings by said tabs, when the cover is closed.
